UNITED STATES PATENT OFFICE

HERBERT G. BEEDE, OF PAWTUCKET, RHODE ISLAND

STEAMING BOARD

Application filed November 26, 1928. Serial No. 322,011.

This invention relates to a steaming board adapted to be used individually or in connection with a garment pressing machine for applying steam to the garment or other fabric upon or in proximity to the surface of the steaming board for moistening and softening said garment or fabric preparatory to pressing, shaping or other treatment thereof.

10 The invention also contemplates means for expeditiously removing the moisture from the garment or other fabric following the moistening, pressing and shaping operations for drying purposes.

15 These steaming boards when used in connection with garment pressing machines of the class set forth in my Patent No. 1,661,153, dated March 6, 1928, are commonly known as bucks but when used in-

20 individually or in connection with the pressing machine they are preferably provided with a heating chamber and a steam distributing chamber, the heating chamber being constantly supplied with steam for main-

25 taining a proper temperature of the buck or steaming element while the distributing chamber is preferably supplied with steam from some available source of supply at the will of the operator and is provided with steam exits through its top wall for liberating the steam to the garment or fabric on the upper surface of the steaming element.

These steam exits from the distributing chamber are formed in a preferably narrow 35 central lengthwise zone of the upper surface of the steaming element the major portion of the length thereof so that when the steam is discharged through the exits it will automatically distribute itself by its own expansive force from the center toward the marginal edges of said element for moistening an area of the fabric at least equivalent to the surface area of the steaming element.

40 One of the objects of the invention, however, is to divide this distributing chamber into separate compartments and to provide simple and efficient means under the control of the operator whereby the steam may be distributed through the surfaces of all of 45 the compartments simultaneously or through

the surface of one of the compartments independently of the others thus permitting economic conservation of the steam, particularly when operating upon small garments or small portions of large garments 55 when only a relatively small portion of the surface area of the steaming element is required.

A further object is to provide simple and efficient means under the control of the operator for withdrawing the steam and moisture from the surfaces of all of the compartments simultaneously or from the surface of one of the compartments only according to the nature of the work operated upon for 65 moistening purposes.

The supply of steam to the plural compartments is controlled by one valve while the supply of steam to one of the compartments may be cut off by another valve and 70 the exhaust of the steam from all or one of the compartments is controlled by a third valve and all of these three valves are controlled by separate pedals through the medium of separate connections hereinafter 75 more fully described and one of the objects of the present invention is to construct and assemble these pedals in such manner that they may be individually operated in the same order from either side of the machine 80 without necessitating the changing of position of the operator.

Another object is to enable the pedal which controls the cut-out valve for one of the compartments to be operated simultaneously with either the steam controlling 85 pedal or the exhaust controlling pedal.

Other objects and uses relating to specific parts of the machine will be brought out in the following description.

In the drawings:

Figure 1 is a side elevation, partly in section, of a fabric moistening and drying machine embodying the various features of my invention.

Figure 2 is an enlarged top plan of the pedals in their operative relation for controlling the steam supply valve, the steam exhaust valve and the cut-out valve.

Figure 3 is an end view of one shaft and 100

reversely arranged pedals, together with the adjacent parts of the means for transmitting motion from said pedals to the exhaust valve.

5 Figure 4 is a top plan, partly broken away, of my improved steaming board.

Figure 5 is a longitudinal section of the steaming board, taken in the plane of line 5-5, Figure 4.

10 Figure 6 is a horizontal sectional view of the steaming board or buck taken in the plane of line 6-6, Figure 5.

Figure 7 is an enlarged longitudinal vertical sectional view through one end of the 15 steaming board taken in the plane of line 7-7, Figure 6.

Figure 8 is an enlarged longitudinal vertical sectional view taken in the plane of line 8-8, Figure 6.

20 Figures 9 and 10 are enlarged transverse vertical sectional views taken respectively in the planes of lines 9-9 and 10-10, Figure 6.

Figure 11 is a longitudinal vertical section 25 view partly broken away, taken in the plane of line 11-11, Figure 13.

Figure 12 is a transverse vertical sectional view taken in the plane of line 12-12, Figure 11.

30 Figure 13 is an end view of the several pedal levers and their supporting shafts, together with the adjacent yokes and crank arms on the shafts for operating the yokes.

The steaming board or buck 35 1 may be mounted in a substantially horizontal position upon any suitable supporting frame or standard 2' adapted to rest upon a floor or other support and comprises a hollow elongated element 2 of cast metal or

40 equivalent material having a steam heated chamber 3 and a steam distributing chamber 4, the member 2 being tapered longitudinally to conform to the shape of certain classes of clothing such as

45 trousers, skirts and the like which are to be treated.

The steam heated chamber 3 is disposed in a plane beneath the steam distributing chamber 4 and is approximately 50 coextensive with the surface area of the steaming board but wholly within the marginal edges thereof and is divided by a central lengthwise partition 5, Figure 6, into opposite lengthwise compartments, said 55 partition extending the major portion of the length of the steaming board but terminating relatively short distances from the ends thereof to establish communication between the compartments or rather to per-

60 mit the outflow of the steam through one compartment from the wider and to the narrower end of the steaming board and return through the other compartment to the end of the partition adjacent the wider end of the 65 steaming board for the purpose of main-

taining uniform distribution of the steam heat throughout the area of the steam heated chamber.

The end of the partition 5 adjacent the wider end of the steaming board is provided with a rearwardly extending transverse partition 6 united to the rear wall of the heating chamber 3 or rear compartment thereof to form the adjacent end wall of the rear compartment and thereby to cut off direct communication between said rear compartment and wider end of the heating chamber, said transverse partition 6 being arranged in spaced relation to the wider end wall of the heating chamber to form what may be termed the steam-receiving end or supplemental compartment 7 of said chamber.

The wider end of the partition 5 is provided with a laterally projecting flange 8 having its front edge curved toward the smaller end of the steaming board and in spaced relation to the front wall of the steam heated chamber 3 to form a connecting passage 9 between the supplemental compartment 7 and front compartment of said chamber, as shown more clearly in Figure 6.

Steam is admitted to the supplemental compartment 7 through an inlet opening 10 in the bottom thereof, said opening being connected by a pipe 11 to any available source of steam supply.

The partition 6 is provided with an opening 6' near the bottom of the chamber 3 and some distance to the rear of the openings 10 and 15 to allow drainage of the water from the chamber 7 into the sump 14.

The wider end wall of the steam heated chamber 3 is provided with a relatively short inwardly projecting central lengthwise partition 12 terminating some distance from the adjacent end of the partition 5 so as to form an intervening steam passage 13 connecting the supplemental chamber 7 with the corresponding end of the front compartment of the chamber 3 so that steam entering the inlet 10 may pass from the supplemental compartment 7 through the passage 13 and thence along the front compartment and return around the opposite end of the partition 5 through the rear compartment to the transverse partition 6.

The bottom of the end of the rear compartment adjacent the transverse partition 6 is disposed some distance below the bottom of the remaining portions of the chamber 3 to form what may be termed a sump chamber 14 for receiving water of condensation and any foreign matter or impurities carried thereby.

The bottom of the sump chamber is pro-

- vided with a drainage outlet —15— to which is connected a pipe —16— leading to any suitable source of discharge, as shown more clearly in Figure 8, the bottom wall 5 of the chamber —3— being preferably inclined from the narrower end of the steaming board toward the sump chamber —14— to facilitate the drainage of water of condensation from the chamber —3—.
- 10 The partition —5— is provided near the bottom wall of the chamber —3— with longitudinally spaced transverse openings —17— to permit steam to pass therethrough from the front compartment to the rear compartment in addition to the passage of the steam around the end of the partition adjacent the narrower end of the steaming board thus obtaining a more rapid and uniform distribution of the steam throughout 20 the area of the steam heated chamber for quickly heating the walls of said chamber.
- The partitions —5—, —6— and —12— and also the top wall of the chamber —3— are preferably formed integral with the element —2—, the lower and upper walls of the heating chamber being supported in fixed relation by said partitions and also by additional tie pieces —18—, as shown in Figure 6.
- 25 The steam distributing chamber —4— is formed in the upper side of the element —2— along the longitudinal center thereof and is relatively narrow transversely but extends the major portion of the length of said element, and, therefore, the major portion of the length of the underlying portion of the chamber —3— so that the top wall of the heating chamber forms the bottom wall of the distributing chamber.
- 30 It, therefore, follows that the steam entering the distributing chamber will be heated to approximately the temperature of the steam in the heating chamber —3— which is desirable in machines of this character for reducing the moisture content of the steam 35 which is applied to the articles to be treated.
- The distributing chamber —4— is provided with a substantially flat and rectangular top wall —19— preferably of sheet metal substantially coextensive with the area of said chamber except that its marginal edges extend beyond the walls of the chamber and are secured by screws —20— or equivalent fastening means to the marginal walls of 45 the distributing chamber, as shown more clearly in Figures 4 and 5, said plate —19— being foraminous in that it is provided with a series of relatively small perforations 50 arranged in more or less uniformly spaced relation throughout the area of the underlying portion of the chamber —4—, the intermediate portions of said plate being supported by spaced lugs —22— projecting upwardly from the bottom wall of the chamber —4—.
- 55 The steam distributing chamber is divided intermediate its ends by a transverse partition —23—, Figure 5, thereby forming opposite end compartments —4'— and —4''— to which steam may be supplied in a manner hereinafter described so that both compartments may be used for supplying steam to a garment on the plate —19— or steam 60 may be supplied to one of the compartments as —4''— independently of the other compartment when operating upon relatively small articles or small portions of larger articles thus permitting the economic conservation of the steam and reducing the liability of escape of excessive steam into the room in which the machine is located.
- The transverse partition —23— is located between the larger end of the partition —5— and narrower end of the steaming board or some distance toward said narrower end from the larger end of the partition.
- This larger end of the partition —5— is provided with a vertical opening —24— extending through the bottom of the element —2— and connected by a pipe —25— to a suitable exhaust device, presently described, the upper end of said opening —24— being in open communication with one end of a 65 branch passage —26— having its other end communicating with a steam-receiving chamber —27— in the lower wall of the distributing chamber —4—, as shown in Figure 5.
- 70 That is, the chamber —27— is depressed below the level of the remaining portions of the distributing chamber —4— while the branch passage —26— is depressed below the plane of the chamber —27— so that the opening —24— leads from the lower part of the passage —26—.
- A horizontal partition plate —28— is secured by screws —28'— or other fastening means to the upper face of the top wall of the steam heated chamber —3— and extends from the under side of the transverse partition —23— to the end of the chamber —4— nearest the large end of the steaming chamber in spaced relation to and preferably 75 parallel with the overlying portion of the top plate —19— so as to form the bottom of the compartment —4'— of the distributing chamber —4—.
- 80 The chamber —27— communicates with the compartment —4''— through an opening or port —29— at the corresponding side of the transverse partition —23— and is relatively narrower transversely than the chamber —4— to serve the double purpose of conducting steam to and from the compartment —4''— of the distributing chamber —4—.
- 85 The plate —28— forms the top wall of 90

the chamber —27— and passage —26— and is provided with an opening or port —30— registering with the inner enlarged end of the partition —12— near the wider end of the steaming board.

A baffle plate —31— is secured to the upper face of the bottom wall of the chamber —27— to extend across the upper end of the opening —24— and also to form a part of the top wall of the branch passage —26— which communicates with the chamber —27— through an opening —32— at the inner end of the baffle plate —31—.

The partition —12— is provided with a vertical opening —33— in which is secured a bushing —34—, Figure 7, the opening —33— and bushing —34— being arranged in vertical alinement with the opening —30— in the partition plate —28— and extending from the underside of the adjacent portion of the element —2— across the adjacent portion of the chamber —3—.

The opening or port —30— serves to connect the adjacent end of the chamber —27— with the compartment —4'— of the distributing chamber —4— and is controlled by a valve —35— which is movable in the upper end of the opening —33— and adjacent portion of the chamber —27—, as shown in Figure 7, for a purpose hereinafter described.

The portions of the bottom and top walls of the steam heated chamber —3— between the adjacent ends of the partitions —5— and —12— are provided with vertically registering openings in which is tightly secured the hollow stem —36— of a valve case —37— so that the valve stem may extend across the chamber —3—, the upper end of the stem —36— being threaded and engaged in a threaded aperture in the upper wall of the chamber —3— while the lower end of said stem is threaded and engaged by a lock nut —38— which, in turn, engages the lower face of the adjacent portions of the member —2— to firmly hold the valve case —37— in operative position.

This valve case is provided with two upright interior passages —39— and —40— separated by an upright partition —41— which extends upwardly from the bottom of the valve case —37—.

The upper end of the passage —39— is provided with an inlet port —42— opening directly into the steam heated chamber —3— while the upper end of the other passage —40— is provided with an outlet port —43— communicating directly with the adjacent portion of the chamber —27—.

The lower portion of the partition —41— is provided with a port —44— connecting the adjacent portions of the passages —39— and —40— and controlled by a horizontal valve —45—, Figure 7, which is normally closed by a coiled spring —46— and is

adapted to be opened at will by mechanism presently described.

Steaming means

The valve —45— controls communication between the passages —39— and —40— and in view of the fact that steam is maintained in the chamber —3— for heating purposes it is evident that if the valve —45— is opened the steam from said chamber will pass from the passage —39— through the open port —44— and thence through the passages —40— and —43— into the passage —27— and thence into the distributing chamber —4— where it is free to escape through the perforated plate —19— to the article under treatment on the upper surface of the steaming board.

That is, when the valve —45— is opened the steam from the chamber —3— may pass into the chamber —27— and thence through the passage —29— and —30— into the steam distributing compartments —4'— and —4''— providing the valve —35— is in its open position.

It is obvious, however, that if the valve —35— is adjusted to close the port —30— the steam admitted to the chamber —27— will escape to the compartment —4''— through the outlet —29— of the chamber —27— at the corresponding side of the transverse partition —23— which then prevents the passage of the steam into the compartment —4'—.

Both of these valves —35— and —45— and also the exhaust controlling valve are under the control of the operator in a manner hereinafter described and, it, therefore, follows that the steam may be directed to both of the compartments —4''— and —4'— simultaneously when the valve —35— and —45— are opened or when the valve —35— is closed the steam from the chamber —3— will be discharged only into the compartment —4''—.

The portion of the bottom of the steam heated chamber —3— immediately surrounding the valve stem —36— is made in the form of a pyramid —36'— to break the capillary action or suction of water up through the valve —37— and thereby assists in maintaining a substantially dry buck.

Each compartment —4— and —4''— of the distributing chamber —4— controls about one-half of the surface of the steaming board and inasmuch as the valve —35— is used to cut off communication between the chamber —27— and compartment —4'— it may be technically termed a half-valve in that it controls one-half of the steaming area while the other valve —45— may be termed the steaming valve for the reason that it controls the supply of steam to both of the compartments —4'— and —4''—.

when the valve —35— is opened or when the valve —35— is closed controls the supply of steam to the compartment —4'— independently of the compartment —4—.

5 The exhaust of the steam and moisture from the article under treatment is also controlled by a valve —47—, Figure 1, under the control of the operator in a manner hereinafter described.

10 The self-closing valves —45— and —47— and the self-opening valve —35— are adapted to be operated independently of each other or in certain combinations by somewhat similar mechanisms including a plurality of, in this instance three, similar double pedal levers —48— and —49— and —50— centrally fulcrumed adjacent each other and having their opposite arms provided respectively with similar pedals

20 marked —S—, —H— and —D— which are arranged in sequence but in reverse order at opposite sides of their fulcrums to enable the operator to selectively and successively operate the corresponding valves in the same order from either side the machine, as shown more clearly in Figures 1, 2 and 3.

It may be stated here that the openings —17— and —6'— in the partitions —5— and —6— respectively are made primarily for the purpose of connecting the cores for the adjacent chambers in the process of casting the steaming board and incidentally serve as drainage openings to facilitate the drainage of water of condensation along the bottoms of the chambers —3— and —7— to the sump chamber —14— and drainage outlet —15— leading therefrom.

These pedal levers —48—, —49— and —50— are respectively secured to the front ends of a corresponding number of longitudinally extending shafts —51—, —52— and —53— which are journaled in suitable bearings in the lower portion or base of the pedestal —2'—, Figure 1.

These pedal levers are preferably located in planes approximately midway between the front and rear sides and also approximately midway between the ends of the steaming board and together with the major portion of the steaming board are located in a vertical plane mainly at the right hand side of the pedestal —2'— so as to afford ample space between the pedals and steaming board for the manipulation of the pedal levers.

The shaft —51— upon which the pedal lever —48— is mounted is tubular to permit the passage of the shaft —53— therethrough and extends longitudinally through the major portion of the base of the pedestal —2'— and is provided with oppositely projecting similar crank arms —54— disposed in approximately the longitudinal and transverse vertical planes of or directly be-

low the valve case —37— for engaging the opposite arms of a saddle yoke —55— at opposite sides of the axis of the shaft.

The yoke —55— is provided with a central vertical slot —55'— extending upwardly from the bottom thereof so as to straddle the shafts —51— and —52—, said slot being extended upwardly a sufficient distance above the shaft —52— to permit the necessary vertical movement of the yoke by the rocking of the arms —54— without interfering with the shaft —52—.

The side walls of the slot cooperate with opposite sides of the shaft —51— to guide the yoke —55— in its vertical movement and also to keep the outer ends of the opposite sides of the yoke in alignment with the adjacent ends of the crank arms —54—, the opposite arms of the yoke —55— adjacent the hub of the arms —54— being slotted vertically from the bottom upwardly to receive said arms.

It is now evident that the downward pressure upon either of the pedals —S— will effect a corresponding rocking movement of the tubular shaft —51— and crank arms —54— carried thereby and that this rocking movement in either direction of the crank arms —54— will effect a corresponding vertical movement of the yoke —55—.

This yoke —55— is connected by a vertical rod —56— to one arm of a bell-crank lever —57— which is pivoted at —58— to the underside of the valve case —37—, as shown in Figure 7, and has its other end engaged with one end of another bell-crank lever —59—.

The lever —59— is pivoted at —59'— to the underside of the valve case —37— and its other shorter arm engaged with a plunger —60— which is guided in a bushing in the adjacent side of the valve case —37— in alignment with the valve —45— for opening said valve as the levers —57— and —59— are rocked about their respective pivots by the upward movement of the rod —56—.

This opening movement of the valve —45— permits the passage of steam from the steam heated chamber —3— into the chamber —27— and thence into the distributing chamber —4— throughout the entire area thereof to escape through the perforated top plate —19— of the steaming board in the manner previously described.

Half steaming

The shaft —52— which controls the operation of the half-valve —35—, Figure 7, is disposed in a plane above or directly over the shafts —51— and —53— and carries at one end the pedal ends —H— which are disposed in a vertical plane between the corresponding pedals —S— and —D— and normally are in a horizontal plane slightly

above the adjacent pedals —S— and —D—, as shown in Figure 1, so that either of the pedals —H— may be operated by the foot of the operator simultaneously with the operation of either of the pedals —S— or —D— at the same side for closing the normally open valve —35— when it is desired to cut off the supply of steam to one of the compartments as —4'— and to supply steam 10 to the other compartment as —4"— of the distributing chamber —4—, thus permitting the use of approximately half of the surface of the steaming board for steaming relatively small garments or small portions 15 of larger garments.

The other end of the shaft opposite the pedal end is provided with a pair of oppositely projecting crank arms —61— adapted to engage opposite arms of a yoke —62— 20 similar to the yoke —55— but somewhat shorter vertically by reason of the fact that the shaft —52— is supported above the shaft —53—.

The yoke —62— is supported on the lower 25 end of a vertically movable rod —63—, Figure 1, and has its upper end provided with a head —64— having a vertical guide opening —64'— therein for the reception of the lower end of a valve stem —65— which carries at its upper end the half valve —35— as shown in Figure 7.

The valve stem —65— is yieldingly supported on the head —64— to allow a limited upward movement of the rod —63— and 35 yoke —62— carried thereby after the valve —35— has been closed to assure a positive closing of the valve and for this purpose the valve stem —65— is provided with a shoulder —66— and coiled springs —67— 40 and —67'—.

One of the springs —67— is interposed between the shoulder —66— and upper end of the head —64— while the other spring —67'— is interposed between said shoulder 45 —66— and the lower end of the bushing —35—.

It is now clear that if it is desired to utilize only a part of the surface of the steaming board for steaming purposes as, 50 for example, the part which is registered with the compartment —4"— either one of the pedals —H— may be depressed by the foot of the operator simultaneously with the adjacent pedal —S— thereby opening the valve —45— and closing the valve —35—, the opening of the valve —45— serving to admit steam to the distributing compartment —4"— while the closing of the valve —35— will prevent the entrance of steam 55 from the chamber —27— to the distributing compartment —4"—, as previously explained.

Drying device

This drying device including the valve 65 —7— is controlled by the pedals —D—

through the medium of the shaft —53— which extends from the pedals entirely through and beyond the tubular shaft —51— and is provided with oppositely projecting crank arms —68— adapted to engage the opposite arms of a yoke —69— similar to the yokes —55— and —62—. 70

The yoke —69— is secured to the lower end of an upwardly projecting rod —70— having its upper end connected to a lever 75 —71— which, in turn, is pivoted at —71'— to a bracket on the valve case —47— and has its other end adapted to engage the stem —72— of the valve within the case —47— for opening said valve when the rod —70— is moved upwardly by the turning movement of the shaft —53— in either direction. 80

The valve case —47— and valve therein is of the self-closing type and is connected to a stem supply pipe —73— to which steam 85 may be supplied from any available source.

The outlet side of the valve case —47— is connected by a pipe —74— to the inlet side of a T-pipe —75— having an exhaust pipe —76— adapted to be connected to any 90 suitable waste or soil pipe, not shown.

This T-coupling is connected to the lower end of the exhaust pipe —25— which, in turn, is connected to both compartments —4'— and —4"— of the distributing chamber —4— through the openings —30— and —29—, Figure 5, so that when the valve —47— is opened by one or the other of the corresponding pedals —D— steam will pass through the pipes —73—, and —74— and thence through the T-coupling —75— and outlet pipe —76— across the lower end of the pipe —25— thereby creating more or less suction in the pipe —25— to withdraw steam and moisture from the distributing chamber —4—. 100

Or, if the steam is used in the compartment —4"— only for moistening purposes the steam and moisture may be withdrawn therefrom independently of the compartment —4"— by simply closing the valve —35— simultaneously with the opening of the valve —47— which may be accomplished by the simultaneous depression of adjacent pedals —D— and —H— by the foot of the operator. 110

Operation

If, in the operation of the steaming board, it is desired to utilize the entire surface of the steaming board for moistening purposes it is simply necessary to depress one or the other of the pedals —S— which through the medium of its connections with the plunger —60— will open the valve —45— thereby 120 allowing steam to pass from the heating chamber —3— through the passages —39— and —40—, through the chamber —27— and thence through the passages —29— and —30— into the distributing chamber —4— 125 130

from which the steam is discharged through the perforated plate —19— and into the garment on the surface of the steaming board.

If it is desired to introduce steam into the compartment —4''— of the distributing chamber —4— independently of the compartment —4'— it is simply necessary to depress one or the other of the pedals —S— and the adjacent pedal —H— which through the medium of its connections with the valve —35— will cause said valve to close the port —30— thereby cutting off communication between the steam chamber —27— and steam distributing compartment —4'—, it being understood that the steam is then free to escape into the compartment —4''— at the corresponding side of the partition —23—, the latter serving to prevent the passage of steam from the compartment —4''— to the compartment —4'—.

When it is desired to exhaust the steam and moisture from the article under treatment on the surface of the steaming board it is simply necessary to depress one or the other of the pedals —D— which through the medium of its connection with the valve —47— will open said valve, thereby allowing the steam to discharge across the lower end of the exhaust pipe —35— for creating suction therein sufficient to withdraw the steam and moisture from the distributing chamber —4— and to discharge the same through the pipe —76— of the T-coupling —75—.

After the steam has been used in the compartment —4''— only for moistening purposes one or the other of the pedals —H— may be depressed simultaneously with the depression of the adjacent pedal —D— for closing the valve —35— and thereby directing the suction entirely to the compartment —4''—.

Owing to the fact that the pedals —H— are disposed in a plane slightly above and between the normal planes of the adjacent pedals —S— and —D— it is evident that the pedal —H— will be operated to close the valve —35— just ahead of the opening of the steaming controlling valve —45— or exhaust valve —47—, this operation being of considerable importance in the use of the machine for the reason that it is desirable to close the valve —35— just preceding the admission of steam into the compartment —4''— and for the further reason that it is desirable to close the valve —35— just preceding the opening of the valve —47— for exhaust purposes.

Although I have described in detail the various parts of the garment steaming machine it will be evident that many of these details may be changed without departing from the spirit of the invention.

What I claim is:

1. In a fabric steaming machine, a buck having a steam-heated chamber, a steam-receiving chamber connected to the heating chamber for receiving steam therefrom, and a steam-distributing chamber having steam exits for directing steam to the fabric, a transverse partition dividing the distributing chamber into opposite end compartments having separate inlet ports communicating with the receiving chamber, a valve controlling the passage of steam from the heating chamber to the receiving chamber, and a separate valve controlling one of said ports independently of the first-named valve. 70

2. In a fabric-steaming machine, a buck having separate steam distributing compartments provided with steam exits leading therefrom through the upper surface of the buck, a steam heated chamber underlying said compartments and having separate passages leading therefrom to said compartments, a normally closed valve controlling one of said passages, a normally-open valve controlling the other passage, and separate devices operable at will for opening the first-named valve and for closing the second-named valve respectively. 85

3. In a fabric-steaming machine, a buck having a steam-heated chamber, separate steam-distributing compartments provided with steam exits leading therefrom through the upper surface of the buck, a steam-receiving chamber receiving steam from the steam heated chamber and provided with separate passages leading to the separate compartments, a normally closed valve controlling the passage of steam from the heated chamber to the receiving chamber, means for opening said valve, a normally open valve controlling the steam passage to one of the compartments, and means for closing the second named valve while the first named valve remains open whereby the steam supply to one compartment is cut off while supplying steam to another compartment. 95

4. A steaming board having a steam heated chamber, and separate steam distributing compartments having steam exits leading therefrom through the upper surface of the board, said board having a steam receiving chamber and separate passages leading therefrom to said compartments and to the heating chamber, a normally closed valve controlling the passage from the heating chamber to the receiving chamber, a normally open valve controlling one of the other passages, a steam operated exhaust device connected to said receiving chamber, a normally closed valve controlling the steam to said device, and means for opening the last named valve independently of the other valves. 115

5. A steaming board having separate 120

- steam distributing compartments and steam exits leading from said compartments through the upper surface of the board, means for supplying steam to each of said compartments, steam operated means for exhausting steam from said compartments, and separate devices operable at will for cutting off the supply of steam to one of the compartments independently of the other compartment and for permitting the passage of steam to the exhausting means, said devices including separate pedals arranged adjacent one another to permit them to be operated simultaneously by one foot of the operator.
6. A steaming board having a steam distributing chamber and steam exits leading therefrom through the upper surface of the steaming board, means including a valve for supplying steam to said chamber, and operating means for said valve including a lever fulcrumed intermediate its ends to move about an axis transversely of and below the longitudinal center of the board and having each end provided with a pedal, and means actuated by the depression of either pedal for opening said valve.
7. In a steaming board of the character described having a steam distributing chamber divided into separate opposite end compartments, each compartment having steam exits leading to the upper surface of the board, means for supplying steam to both of said compartments, a normally closed valve controlling the supply of steam to both of said compartments, a normally open valve for cutting off the supply of steam to one of the compartments, means including a pedal for opening the first-named valve, and means including a pedal for closing the second-named valve.
8. In a steaming board of the character described having a steam distributing chamber divided into separate opposite end compartments, each compartment having steam exits leading to the upper surface of the board, means including a normally closed valve for directing steam to both of said compartments simultaneously, a normally open valve controlling the supply of steam to one of the compartments independently of the first named valve, means including a pedal for opening the first-named valve, and means including a pedal for closing the second-named valve, said pedals being juxtaposed for simultaneous operation by the foot of the operator.
9. In a steaming board of the character described having a distributing chamber divided into separate compartments, each compartment having steam exits through the upper surface of the board, means for supplying steam to said compartments, means for exhausting the steam from said compartments, and means for cutting off communication between said exhausting means and one of the compartments while maintaining communication between said exhausting means and another compartment.
10. In a steaming board of the character described having a distributing chamber divided into separate opposed end compartments, each compartment having steam exits through the upper surface of the board, means for supplying steam to said compartments, means operable at will for controlling the supply of steam to said compartments, means operable at will for controlling the exhausting means, and means operable at will for cutting off communication between one of the compartments and the steam supplying means and also for cutting off communication between the same compartment and the exhausting means.
11. In a steaming board of the character described having a distributing chamber divided into separate opposed end compartments, each compartment having openings extending therefrom through the upper surface of the board, means for supplying steam to said compartments, means for exhausting steam from said compartments, a normally closed valve controlling the steam supply to said compartments, a normally closed valve controlling the exhausting means, means including a normally open valve for controlling communication between one of the compartments and the steam supply means and also controlling communication between the same compartment and the exhausting means, means including a pedal for opening the steam supply valve, means including a pedal for opening the exhaust valve, and means including a pedal for closing the cut off valve.
12. In a steaming board of the character described having a distributing chamber divided into separate compartments, each compartment having openings extending therefrom through the upper surface of the board, means for supplying steam to said compartments, means for exhausting steam from said compartments, a normally closed valve controlling the steam supply to said compartments, a normally closed valve controlling the exhausting means, means including a normally open valve for controlling communication between one of the compartments and the steam supply means and also controlling communication between the same compartment and the exhausting means, means including a pedal for opening the steam supply valve, means including a pedal for opening the exhaust valve, and means including a pedal for closing the cut off valve.
13. The combination with a steaming

board arranged to permit the manipulation of the work thereon from opposite sides thereof and provided with a steam distributing chamber having exit openings through its upper wall, a valve controlling the passage of steam to said chamber, pedally operated rock arms extending in opposite directions from their axes toward opposite sides of the steaming board, and means actuated by the operation of either of said arms in the same direction for opening the valve.

14. The combination with a steaming board arranged to permit the manipulation of the work thereon from opposite sides thereof and provided with a steam distributing chamber having exit openings through its upper wall, a rock shaft extending lengthwise of and beneath the steaming board and provided with oppositely projecting treadles operable at will by the operator at opposite sides of the machine for rocking the shaft in reverse directions, and means actuated by the rocking of the shaft in either direction for opening the valve.

15. The combination with a steaming board having a steam distributing chamber provided with steam exits through its upper wall, means including a valve for supplying steam to said chamber, and means including a valve for creating suction in said chamber, of levers pivoted intermediate their ends to rock about axes extending lengthwise of and some distance below the steaming board so that the opposite ends of the levers may face opposite sides of the steaming board to be depressed by the operator at either side, means actuated by the depression of either side of one of the levers for opening one of the valves, and additional means actuated by the depression of either side of the other lever for opening the other valve.

16. A steaming board as in claim 15 in which the outer ends of the valve-operating levers are arranged side by side lengthwise of the steaming board but in reverse order.

17. In a fabric steaming device, a buck having a steam-heated chamber and a steam-distributing chamber provided with a perforated top wall, said buck having a central lengthwise partition dividing the heating chamber into opposite lengthwise compartments having connecting passages around both ends of the partition, means including a normally closed valve adapted to be opened at will for directing steam from one of said passages to the distributing chamber, said partition being provided with an exhaust port therethrough communicating with the distributing chamber, and a steam operated exhaust device connected to the exhaust port and provided with a normally closed valve adapted to be opened at will for exhausting steam from the distributing chamber.

18. In a steaming board of the character

described, a buck having a steam heated chamber and an overlying steam distributing chamber provided with a perforated top wall, said buck having a central lengthwise partition dividing the heating chamber into opposite lengthwise compartments having connecting passages around both ends of the partition, means for introducing steam into one of said passages for circulation through said compartments, means including a normally closed valve adapted to be opened at will for directing steam from the heating chamber to the distributing chamber, said partition having an exhaust port extending therethrough and communicating with the distributing chamber, and a steam operated exhaust device connected to said port for exhausting steam from the distributing chamber.

19. A fabric-steaming board having a steam heated chamber, a steam distributing chamber overlying the heating chamber and provided with a perforated top wall and a transverse partition dividing it into opposite end compartments, and an intermediate steam-receiving chamber between the heating chamber and one of said compartments and connected through separate passages with both compartments, means including a normally closed valve adapted to be opened at will for directing steam from the heating chamber to the intermediate chamber and thence through said passages to the distributing chamber, and a normally open valve controlling one of said passages and adapted to be closed at will.

20. A steaming board as in claim 19 in which a steam operated exhaust device is connected to the intermediate chamber and provided with a normally closed valve adapted to be opened at will for withdrawing the steam from the intermediate chamber and from the distributing chamber.

21. In a steaming board, a buck having a steam heated chamber provided with a central lengthwise partition dividing it into opposite lengthwise compartments having connecting passages around opposite ends of the partition, said chamber having a sump near one end of the partition provided with a drainage outlet, the bottom of said chamber being inclined downwardly toward said sump for draining water of condensation through, the partition being provided with a transverse opening intermediate its ends near the bottom of the chamber to allow water of condensation to drain therethrough to the sump.

22. A steaming board having a steam heated chamber and a steam distributing chamber overlying the heating chamber and provided with a perforated top wall, said heating chamber having a lengthwise partition dividing it into opposite lengthwise compartments having connecting passages

around opposite ends of the partition, means for introducing steam into said chamber at one end of the partition, means for conducting steam from the passage at one end of the partition to the distributing chamber, and a normally closed valve adapted to be opened at will for controlling the passage of steam through said conducting means, said partition being provided with an exhaust port communicating with the distributing chamber and steam operated exhaust means connected to said port for withdrawing the steam from the distributing chamber.

15 In witness whereof I have hereunto set my hand this 6th day of November, 1928.

HERBERT G. BEEDE.
